US00D729832S

(12) **United States Design Patent**
Izotov et al.

(10) **Patent No.:** **US D729,832 S**
(45) **Date of Patent:** **** May 19, 2015**

(54) **DISPLAY SCREEN WITH GRAPHICAL USER INTERFACE**

(71) Applicant: **Microsoft Corporation**, Redmond, WA (US)

(72) Inventors: **Dmytro Izotov**, London (GB); **Christopher James Clare**, Burlingame, CA (US); **Torsten Rehberg**, London (GB)

(73) Assignee: **Microsoft Corporation**, Redmond, WA (US)

(**) Term: **14 Years**

(21) Appl. No.: **29/459,438**

(22) Filed: **Jun. 28, 2013**

(51) LOC (10) Cl. **14-04**

(52) U.S. Cl. **USPC D14/486**

(58) **Field of Classification Search**

USPC D14/485-495; D18/26, 31, 32, 33; D20/11, 12, 23, 24, 25, 29, 30, 31, 32, D20/36, 37, 38; 715/702, 764, 838
